ADJUSTABLE LADDER LEG

Benn F. Fenton, Kansas City, Mo.

Application April 27, 1937, Serial No. 139,222

9 Claims. (Cl. 228—63)

My invention relates to an adjustable leg for preventing a ladder from inclining in a transverse direction from the perpendicular when standing on an inclined or irregular surface, and one object is to provide a leg of this character which may be adjusted longitudinally upon either of the side rails of the ladder to accommodate the same to such irregular supporting surfaces as may be encountered when the ladder is used by a painter, carpenter, or other workman.

A further object is to provide simple and efficient means for reliably securing the adjustable leg at any point of its adjustment upon one of the rails of the ladder, such securing means being adjustable to accommodate rails of different sizes.

Other objects will hereinafter appear and in order that the invention may be fully understood, reference will now be had to the accompanying drawing, in which:

Fig. 1 is a broken front elevation of a ladder equipped with my device.

Fig. 2 is an enlarged broken longitudinal section on line 2—2 of Fig. 1.

Fig. 3 is an irregular cross section on line 3—3 of Fig. 2.

Fig. 4 is a perspective view of certain parts of the device.

Referring in detail to the different parts, A designates a ladder which may be of ordinary construction comprising side rails B and rungs C.

Referring now more particularly to the device forming the present invention, 2 designates an adjustable leg of suitable length and adapted to slide longitudinally upon the face of either of the rails B. The leg 2 is held in position against the face of one of the rails B by means of a member 4 and one or more clamp means hereinafter described. The member 4 consists preferably of sheet metal and comprises two side walls 8 spaced apart and a transverse rear wall 10, which latter unites the former. The front of the member 4 is left open so that it may be readily placed in position upon one of the rails B and the leg 2.

The lower edges of the side walls 8 are provided with recesses 12 either of which is adapted to fit over a rung C of the ladder. The lower edges of the side walls 8 are also curved as indicated at 14, so that they may readily clear the adjacent rung C when the member 4 is applied to or removed from one of the rails B. The upper portion of the side walls 8 have respective upward extensions 16 either of which is adapted to fit against the forward portion of the adjacent rung C and thus coat with the recesses 12 in holding said member 4 in position upon the ladder.

In order to prevent the member 4 from being

moved upward accidentally and thereby disengaging its recessed portion 12 from the adjoining rung C, I provide one of the side walls 8 with a slide 17 for engagement with the under portion of said rung C. The slide 17 is operably mounted in a guide 18 fixed to the adjacent side wall 8 and provided with a longitudinal slot 19. Studs 20, fixed to the slide 17, project through the slot 19 and are provided with washers 22 and nuts 24 to coat therewith in securing the slide against the rung.

Suitable clamp means are provided for pressing the side walls 8 into frictional engagement with the leg 2 and the adjacent rail B to prevent the former from slipping upon the latter when the ladder is in use. The clamp means may be separate from the member 4, but to prevent loss or displacement I prefer to mount said clamp means permanently upon one of the side walls 8. As best shown by Fig. 3, said clamp means comprises a member 26 and a set screw 28, which latter is threaded in one end of the former. The member 26 is approximately C-shaped to overlap both of the side walls 8, to one of which it is hingedly connected by a member 30. The member 30 has a longitudinal slot 32 through which a stud 34 projects from the adjoining side wall 8. The foregoing arrangement permits the members 30 and 26 to be adjusted forward or backward to accommodate rails B of different widths, it being apparent that a wide rail will force the leg 2 outward to a greater extent than a narrow rail and the member 30 must be adjusted accordingly so that it may close against the face of said leg as shown by Fig. 3. The stud 34 is provided with a washer 36 and a nut 38 to coat therewith in securing the member 30 at any point of its adjustment. The inner end of the set screw 28 is preferably of conical form as shown so that when said set screw is adjusted inwardly with a wrench it will imbed the adjoining portion of the associated side wall 8 into the leg 2 more or less and thereby eliminate all chance of accidental slippage of said leg in the member 4, when the ladder is in use. Preferably the member 4 is provided near each end with clamp means, so that the side walls 8 may be reliably held in engagement with the leg 2 and associated rail B.

The device may be readily applied to a ladder by tilting the upper end of the member 4 forward and engaging the rear edge of one of the extensions 16 with one of the rungs B, preferably the third one from the lower end of the ladder. The lower end of the member 4 is then swung forward over the underlying rung and then lowered to engage the adjacent recess 12 over the last-mentioned rung. The leg 2 may then be placed between the side walls 8 and against

the face of the associated rail B and firmly secured in place with the clamp means above described.

In order to overcome any possibility of the lower part of the adjustable leg 2 from swinging away from the lower end of the ladder rail B, I provide another clamping means somewhat similar to the one above described, excepting that the sheet metal member 4a is only about half the length of the member 4 and may be equipped with but one clamping member.

From the foregoing description it is apparent that I have provided an adjustable leg and means for securing it to a ladder which are well adapted for the purpose intended, and while I have shown and described one form of my invention I reserve the right to all other forms which properly fall within the spirit and scope of the invention as claimed.

Having thus described my invention, what I claim and desire to secure by Letters Patent, is:

1. A device of the character described comprising a leg adapted to be adjusted longitudinally on either rail of a ladder, a member adapted to embrace said leg and the adjacent rail and having a recess at its lower end to fit over one of the ladder rungs, and clamp means for forcing said member into frictional engagement with the leg and the rail to prevent the former from slipping upon the latter.

2. A device of the character described comprising a leg adapted to be adjusted longitudinally on either rail of a ladder, a member adapted to embrace said leg and the adjacent rail having a recess at its lower end to fit over one of the ladder rungs and an extension at its upper end to bear against another rung, and means for forcing said member into frictional engagement with the leg and the rail to prevent the former from slipping upon the latter.

3. A device of the character described comprising a leg adapted to be adjusted longitudinally on either rail of a ladder, a member adapted to embrace said leg and the adjacent rail of the ladder and rest upon one of the ladder rungs, adjustable means at the upper portion of said member adapted to engage the under portion of another rung, means for securing said adjustable means in position against the last-mentioned rung, and means for forcing said member into frictional engagement with the leg and the rail to prevent the former from slipping upon the latter.

4. A device of the character described comprising a leg adapted to be adjusted longitudinally on one rail of a ladder, a member adapted to embrace said leg and the adjacent rail and rest upon one of the ladder rungs, a slide operably mounted at the upper portion of said member adapted to engage the under portion of another rung, slotted guide means for said slide, stud bolts fixed to the slide and projecting through said slotted guide means, nuts threaded upon said stud bolts and adapted to coact therewith in preventing accidental movement of the slide, and means for forcing said member into frictional engagement with the leg and the rail to prevent the former from slipping upon the latter.

5. A device of the character described comprising a leg adapted to be adjusted longitudinally on one rail of a ladder, a member adapted to embrace said leg and the adjacent rail and

rest upon one of the ladder rungs, the lower end of said member being curved forwardly and upwardly, an extension on the upper end of said member adapted to engage the forward portion of another rung, and means for forcing said member into frictional engagement with the leg and the rail.

6. A device of the character described comprising a leg adapted to be adjusted longitudinally on one rail of a ladder, a member comprising a rear wall and two spaced side walls which latter are connected to the former, said rear wall being adapted to bear against the rear surface of the rail and said side walls being adapted to bear against opposite sides of the leg and the rail, extensions at the upper portion of said member adapted to bear against the forward portion of a rung, and means for forcing said side walls into frictional engagement with the respective sides of the leg and the ladder.

7. A device of the character described comprising a leg adapted to be adjusted longitudinally on one rail of a ladder, a flexible member comprising a rear wall and two spaced side walls which latter are connected to the former, said rear wall being adapted to bear against the rear surface of the rail and said side walls being adapted to bear against opposite sides of the leg and the rail and either of which is also adapted to rest upon one of the ladder rungs, upward extensions at the upper portion of the flexible member adapted to bear against another rung, adjustable means at the upper portion of one of the side walls adapted to engage the under portion of the last-mentioned rung, and means for forcing said side walls into frictional engagement with the respective sides of the leg and the ladder.

8. A device of the character described comprising a leg adapted to be adjusted longitudinally on one rail of a ladder, a flexible member comprising a rear wall and two spaced side walls which latter are connected to the former, said rear wall being adapted to bear against the rear surface of the rail and said side walls being adapted to bear against opposite sides of the leg and the rail and either of which is also adapted to rest upon one of the ladder rungs, a slide operably mounted at the upper portion of one of the side walls adapted to engage the under surface of another rung, means for securing said slide in engagement with the last-mentioned rung, and means for forcing said side walls into frictional engagement with the respective sides of the leg and the ladder.

9. A device of the character described comprising a leg adapted to be adjusted longitudinally on one rail of a ladder, a member having two walls spaced apart and adapted to bear against opposite sides of the leg and the rail, a hinge-member adjustably connected to one of said side walls so that it may be moved toward or away from the front edge thereof, means for securing said hinge member at any point of its adjustment, a clamp member of approximately C-form pivoted at one end to said hinge member adapted when in active position to bear against the front surface of the leg and overlap the other side wall, and an element adapted to bear against the last-mentioned side wall and threaded in said clamp member to coact therewith in forcing the side walls firmly against the leg and the rail.
